UNITED STATES PATENT OFFICE.

JEREMIAH D. BURNS, OF WASHINGTON, DISTRICT OF COLUMBIA.

BUTTON BELT-LOOP ATTACHMENT FOR GARMENTS.

SPECIFICATION forming part of Letters Patent No. 758,350, dated April 26, 1904.

Application filed June 29, 1903. Serial No. 163,645. (No model.)

To all whom it may concern:

Be it known that I, JEREMIAH D. BURNS, a citizen of the United States, and a resident of the city of Washington, in the District of Columbia, have invented an Improved Button Belt-Loop Attachment for Garments, of which the following is a full description.

My invention is a novel, inexpensive, easily-applied, and highly-practical attachment for use in garments to which buttons are usually applied, and especially on trousers and knee-breeches for securing belts and suspender-ends thereto.

The details of construction, application, and arrangement of the device are hereinafter described under various modifications, reference being had to the accompanying drawings, in which—

Figure 1 is a face view illustrating the application of one form of my invention to the waistband of trousers for securing the belt and suspender-ends thereto. Fig. 2 is an enlarged cross-section on the line 2 2 of Fig. 1. Fig. 2^a is another cross-section illustrating the attachment of a modified form of the device. Fig. 3 is a face view of the device shown in Figs. 1 and 2, and Fig. 4 is a side view of the same. Fig. 5 is a sectional view illustrating a modification in the attachment of the device to the trousers. Fig. 6 is a perspective view illustrating the manner of attaching the device to a garment. Fig. 7 is a cross-section on the line 7 7 of Fig. 8, illustrating the attachment of a modified form of the device to the waistband of the trousers. Fig. 8 is a view illustrating the attachment of the device shown in Fig. 7, the lining of the trousers being shown cut out for clearness of illustration. Fig. 9 is a face view of the attachment represented in Figs. 7 and 8. Fig. 10 is another cross-section of the waistband of the trousers, illustrating the application of a second modified form of the device. Fig. 11 is a perspective view, part being in section, of my improved device. Figs. 12, 13, 14 are further illustrations of modified forms of the device. Fig. 15 is a side view of the form shown in Fig. 14.

My improved device or attachment is constructed of two principal parts—viz., the head

and an extended shank, which is arranged practically at a right angle to the head and is suitably adapted to be secured to a garment or fabric, as hereinafter described.

In Figs. 1, 2, 3, 4, 11 I illustrate the preferred form and manner of attachment of the device.

Referring especially to Figs. 3 and 4, 1 indicates the head or button, and 2 the extended shank, whose lower end is bent at an angle and provided with a piercing-point 3, which in this case takes the form of a hook. The shank 2 is in all cases flexible and in some cases elastic, it being formed of a metal wire of suitable size and strength. In practice fine piano-wire has proven suitable and efficient. As here shown, the shank 2 is made of such length as to adapt it to span the width of the belt *x*, (see Fig. 1,) such as is usually worn for securing the waistband of trousers *y*. As shown in Fig. 2, the head or button 1 is provided with a central perforation to secure the bent portion of the shank 2, which is constructed with a head or enlargement 2^b on the outer or concave side of the button. Between the button and the longer or extended portion of the shank 2 the latter is formed into a spiral 2^c.

The device is applied as follows: The piercing-point 3 is inserted from the inner side of the waistband of the trousers *y* and passed entirely through the lining, canvas, and cloth, as at the point shown—*i. e.*, at the point where it is desired the button or head 1 shall be located for the attachment of a suspender-end *z*. Such points of location are indicated by dotted lines in Fig. 1. In thus applying the device it is so manipulated by twisting or rotating it as to cause the bent lower end 2^a and the spiral 2^c to pass through the three thicknesses of fabric. (Indicated in Fig. 2.) The next step in the operation is the attachment of the hooked end 2^a to the cloth of the trousers *y*. This is accomplished, as illustrated in Fig. 6, by drawing the cloth together and bending the shank 2 outward, so that the hooked end 2^a may be caught into and inserted through the cloth, and finally occupies the position shown by dotted lines in Fig. 1 and full lines in Fig. 2. When thus applied, the head or button

proper, 1, is firmly attached on the inner side of the trousers y , and the lower or hooked end of the shank 2 is duly secured in place, but does not bear any of the pulling strain incident to the use of the suspenders z , as shown. When thus applied, the body of the shank 2 is alone visible on the outer side of the trousers and forms an inconspicuous but ornamental appendage thereof. The form, length, and attachment of the shank 2 adapts it to serve as a loop for holding the belt and is in this respect far more ornamental and serviceable than the ordinary cloth or tape loop sewed to trousers. Furthermore, the device is easily detachable and may be again reapplied when occasion requires. In brief, it will be seen that my device or attachment performs two functions—viz., it serves in place of the ordinary button usually sewed to trousers and also as a belt-holder or loop which is at once ornamental, strong, durable, easily applied, and detached.

As seen in Figs. 1, 2, 3, the shank or loop 2 is provided with a head by which it is prevented from detachment from the head or button proper, 1. My invention is, however, capable of embodiment in many forms or various modifications, some of which I will proceed to indicate. In Fig. 2^a the shank or loop 2^a is shown without a spiral or coil, and in such case the head or button proper, 1^a, is secured to the garment by stitches. It will be seen, however, that this form of the device permits the shank or loop to be readily attached to or detached from the button or head 1^a, whereas in the case of the device shown in Figs. 1, 2, 3, 4 the head or button 1 must be applied before the spiral 2^c is formed.

Fig. 5 illustrates a slight change in the arrangement of the device or attachment in relation to a garment—*i. e.*, to the waistband of the trousers—the shank 2 being in this case arranged between the lining and the canvas in place of passing through the lining, as in Figs. 2, 2^a.

In Figs. 7, 8, 9 I illustrate a further modification, the shank 2^f being provided with a spiral and a hook 2^g, while its head 2^h is coiled to prevent the shank being drawn through the button or head proper, 1^b. In this case the shank is made very short and is not adapted for use in holding and supporting the belt.

Fig. 10 illustrates another modification, in which the shank 2ⁱ is so curved that it passes twice through the fabric or cloth and lining of trousers y , then extends downward to form a loop of sufficient length to span the belt x , its hooked lower end passing through the cloth, as shown.

Fig. 11 shows the shank of the device as it may be constructed with the offset and a projection extending beyond the same, but with or without the extension forming a hook proper.

In Fig. 12 the shank 2ⁿ is bent laterally, 65 which form has some advantages in respect to facilitating the application of the fingers through the shank for attaching and detaching the hooked end.

Fig. 13 shows a shank 20, secured to a button or head proper, 1^d, having a series of needle and thread holes. In such case the button is secured to the fabric by sewing in the usual way.

In Figs. 14 and 15 a shank 2^p is shown, provided with a head 1^e, which is formed by coiling the wire upon itself. In Fig. 15 such device is shown applied to trousers y and supporting a belt.

It will be understood that I will construct 80 the point of the shank which projects beyond the offset either as a straight extension or as a hook, as illustrated by full and dotted lines in Fig. 11, the extension being in either case in a plane parallel to the body of the shank. 85

In Figs. 3, 4 the free end of the shank 2^a is bent twice practically at a right angle, whereby it is adapted to pass through the fabric or cloth and the hooked portion to lie in a plane parallel with the head or button 1. 90

I claim—

1. The device for the purpose specified comprising a head and a bent shank having one end secured to the head and its opposite free pointed end bent or offset with the point extended 95 beyond the offset whereby it is adapted to engage a fabric, said shank having also a portion intermediate said ends and parallel to said head.

2. A device for the purposes specified comprising a head and a bent shank attached thereto and having its free end bent twice practically at a right angle and formed with a terminal hook which is in a plane parallel to the head, substantially as described. 100

3. In a device for the purposes specified comprising a head, and a bent shank which is attached thereto, the same being elastic and easily flexible, and provided at its free end with an offset adapted to engage a fabric, substantially as described. 110

4. A device for the purposes specified comprising a head, and a bent wire shank which is attached thereto and provided with a coil located between its extended body and the head 115 and having its lower end offset and adapted to engage the fabric, substantially as described.

5. The combination with a garment of the device described consisting of a head and a bent wire shank which is attached to said head and passes through the fabric of the garment and is extended on the outer side of the latter, its end being offset and reinserted through the fabric, substantially as described. 120
